UNITED STATES PATENT OFFICE.

WILLIAM A. LORENZ, OF HARTFORD, CONNECTICUT.

CLOSURE FOR CONTAINERS.

Application filed May 2, 1923. Serial No. 636,266.

To all whom it may concern:

Be it known that I, WILLIAM A. LORENZ, a citizen of the United States, residing at Hartford, in the county of Hartford and 5 State of Connecticut, have invented new and useful Improvements in Closures for Containers, of which the following is a specification.

This invention relates to improved means 10 for closing tops of jars, tumblers or other containers. This closure is adapted for sealing containers, containing cold products without the use of vacuum; or for sealing receptacles by the well known vacuum proc- 15 ess.

The hermetic sealing of containers of the class usually employed, presents difficulties which are quite serious. These comprise the proper seating of the cap and gasket 20 on the jar rim and holding them in place while pumping the air out of the container. This difficulty is increased when substances are to be hermetically sealed which contain much air, like peanut butter. The air 25 causes the substances to ooze out beyond the gasket and causes the cap to assume a crooked position on the container after the sealing operation.

The object of the present invention is to 30 provide a closure which will hold the gasket upon the rim, with just enough pressure, to prevent the contents from oozing out, during the sealing operation. Another object is to provide mechanical means for holding the 35 gasket on the container. These two objects are accomplished by providing several spring catches in the cap. These are formed in the cap rim, and are sprung inwardly, so as to engage a first shoulder on the container. 40 When the sealing operation is performed, the cap is forced downwardly to compress the gasket on the rim of the container, and the spring catches will then engage a secondary shoulder, so as to hold that cap by 45 this mechanical means, in addition to the atmospheric pressure exerted upon the cap.

Another object comprises the packing of 50 hot products by the well known vacuum process. This is accomplished by heating the container; pouring the hot product into the container; putting the cap in place; putting a weight on the top of the cap until the contents of the container cools, and thereby engaging the catches with the jar 55 shoulder.

In the drawings Figure 1 represents a plan

view of a rectangular piece of metal with four corners trimmed off. Fig. 2 is a sectional view of a cap, with a gasket placed upon the container, taken on the line 2—2 60 of Fig. 1. Fig. 3 shows a sectional view of gasket and cap on the container, taken on line 3—3 of Fig. 1. Fig. 4 shows a sectional view of a cap, gasket and container in sealing position taken on the line 4—4 65 of Fig. 1. Fig. 5 shows a plan view of a sheet of metal from which a cap is to be formed. Fig. 6 shows a cap with a gasket in sealing position upon a container taken on the line 6—6 of Fig. 5. Fig. 7 shows a cap, 70 a gasket and a container, taken on the line 7—7 of Fig. 5. Fig. 8 shows the parts of Fig. 7 in sealed position. Fig. 9 shows a sectional view taken on the line 9—9 of Fig. 5, showing a portion of the cap only. Fig. 75 10 shows a method of processing, the containers being placed in boiling water. Fig. 11 shows the receptacles of Fig. 10 removed after boiling, and placed outside where they can cool. 80

The container 12 may be made of any desired form. It is provided with a rounded rim 13 and two shoulders 14 and 15. The cap 16 produced by bending the rim 17 downwardly from the dotted circles, shown, 85 is formed out of the blank 18 (Fig. 1); the cap may be formed from a blank 19 (Fig. 5).

This blank may have four edges 20 cut away, or the cap may be made from a complete disk of metal. 90

Fig. 1 shows three lengths of catches; short catches 22, medium catches 23, and long catches 24.

In Fig. 5 two lengths of catches are shown, as at 23 and 25. In Figs. 6 and 9, the cap 95 is shown bent outwardly.

The cap may also be bent outwardly at intervals, as at 26, 27 and 28. These bends are in the form of dents open at the lower end, and are for the purpose of permitting 100 the insertion of a tool between the cap and the jar so that the cap can be pried from place.

The container 12 of Figs. 2, 3 and 4, is provided with one shoulder only, 29, whereas in Figs. 6, 7 and 8, two shoulders 14 and 15 are provided. 30 shows the gasket in its unsealed position, and 31 shows this gasket in the sealed position. When a cap 16, which is provided with different lengths 105 of catches as 22, 23 and 24, Fig. 1 is placed with its uncompressed gasket upon a con- 110

tainer 12, then either the shorter catch 22 or the medium catch 23 will engage the shoulder 29, so as to hold the cap on the container as shown in Fig. 2. One or other 5 of the two catches 22 and 23 are to provide means for engaging under the shoulder 29, if the length of the shoulder 29 varies in depth from the top of the container. That is, if that shoulder is short, catches 23 can 10 engage the shoulder 29; or if the shoulder is long then catches 22 can engage the shoulder, thus providing for irregularity in the jar or container.

Referring to Fig. 4, it will be seen that 15 the cap in that position has been pressed down and the jar has been sealed. This compresses the gasket 30 to the position 31 and enables the long catches 24 to engage the shoulder 29, and thus adding the mechanical holding devices to the atmospheric 20 pressure that holds the cap down.

In Figs. 6, 7 and 8 the containers 12 are provided with two shoulders 14 and 15. In Fig. 5 two lengths of catches 23 and 25 are 25 shown. When the cap 16 and its gasket 30, is placed upon the container 12, the catches 23 or 25 will engage the first shoulder 14; and when the gasket 30 has been compressed to 31 as in Fig. 8, the catches 23 or 25 will 30 engage the secondary shoulder 15, depending upon the degree of pressure exerted on the cap; or depending upon the differences in shoulder lengths.

For cold sealing, the cap 16 is merely 35 pressed down, until some of the catches engage one of the shoulders on the container, and the gasket is compressed as shown in Figs. 4 and 8.

In processing foods the containers 12 are 40 provided with caps 16 and gaskets, and are placed in a kettle provided with boiling water 36. Upon the caps weights 37 are placed. The kettle is placed upon a stove and the contents may be boiled. Then the 45 containers 12 with the weights are removed, as shown in Fig. 11, and left to cool with the weights on the caps. The contraction of the air inside the container will cause the cap to settle down on the gasket, and permit the catches to engage the shoulders on 50 the container, so as to lock them, in addition to the atmospheric seal.

I claim as my invention:

1. In combination a container having a 55 plurality of shoulders spaced at different distances from the mouth of the container,

and a cap having a rim provided with inwardly bent resilient catches adapted to successively engage said shoulders when the cap is forced into place.

2. In combination a container having a plurality of shoulders spaced at different distances from the mouth of the container, and a closure comprising a cap having a rim provided with a plurality of sets of resilient 65 inwardly bent catches, the effective ends of the catches of the several sets being in different planes, whereby to successively engage said shoulders.

3. In combination, a container having a plurality of shoulders slightly spaced apart at different distances from the mouth of the container, a cap having a rim provided with inwardly bent resilient catches adapted to successively engage said shoulders when the 75 cap is forced in place, and a gasket between the mouth of said container and said cap and compressed there-between when said catches are in locking engagement with any of said shoulders.

4. In combination, a container having a plurality of shoulders slightly spaced apart at different distances from the mouth of the container; a closure comprising a cap having a rim provided with a plurality of sets of 85 resilient inwardly bent catches, the effective ends of said catches of the several sets being in different planes whereby to successively engage said shoulders, and a gasket between said container and closure, said shoulders 90 and said catches being so constructed and arranged that said gasket is compressed when any of said catches are engaged with any of said shoulders.

5. In combination, a container having a 95 plurality of shoulders slightly spaced apart at different distances from the mouth of the container and successively decreasing in diameter, a cap having a rim provided with inwardly bent resilient catches adapted to 100 successively engage said shoulders when the cap is forced in place, and a gasket interposed between the mouth of said container and said cap and adapted to be compressed therebetween when said catches engage any 105 of said shoulders.

Signed at Hartford, Conn., this 27th day of April, 1923.

WILLIAM A. LORENZ.
